United States Patent Office.

DESIGN FOR A SHAFTING HANGER.

C. C. KLEIN, OF PHILADELPHIA, PENNSYLVANIA, ASSIGNOR TO THOMAS WOOD, OF SAME PLACE.

Design No. 2,528, dated December 11, 1866.

The Schedule referred to in these Letters Patent and making part of the same.

TO ALL WHOM IT MAY CONCERN:

Be it known that I, C. C. KLEIN, of Philadelphia, in the county of Philadelphia, and State of Pennsylvania, have produced a new and useful Design for a Shafting Hanger; and I do hereby declare that the following is a full, clear, and exact description of the same, reference being had to the annexed drawings, making part of this specification, in which—

Figure 1 is a side elevation.

Figure 2, an end view.

Figure 3, a plan; and

Figure 3', a horizontal section of the arms.

The ribs *a a* are made similar in curvature, and the webs on the back of them terminate in the chipping pieces *b b*, with the same curve on both sides of the hanger. The webs *c c* are also equidistant from the centre line, and similar to each other. The rib *d* is carried down in a straight line, tangent to the curves *e* and *f*. The web *h* widens out as it approaches the lower boss *K'*, and another web *i* is carried down on the inside of the rib *d*.

I do not claim as my invention the bosses *K K'*, nor the construction of the footing *ll*; but what I claim is—

The design for a shafting hanger, as shown and described.

C. C. KLEIN.
